ABSTRACT: A safety switch to terminate the operation of an automatic appliance when a closure is moved from a closed position is provided including a cabinet-carried escutcheon movable laterally for alignment with an elongate, closure-carried projection adapted to engage a switch actuator disposed beneath the escutcheon. The escutcheon has a substantially centrally located aperture formed therethrough, the aperture being tapered provides a relatively large outer diameter facing the closure carried projection, and a relatively small inner diameter adjacent the interior of the cabinet. The inner diameter of the aperture is sufficiently small to prevent manual operation of the switch by an operator attempting to extend his finger through the aperture.

CLOSURE-OPERATED SAFETY SWITCH FOR AUTOMATIC APPLIANCE

BACKGROUND OF THE INVENTION

In conjunction with many domestic automatic appliances which have a cabinet and a closure member adapted to control access to the interior of the cabinet, it is desirable to provide a closure-operated switch which will terminate the operation of the appliance when the closure is moved from the closed position. A variety of such closure-operated switches are well known in the art and, in fact, are commonly provided on such appliances as automatic fabric washing machines.

One problem inherent in the provision of such switches, however, relates to the fact that an operator may usually reactivate the appliance with the closure in an open position by manually actuating the closure switch. Where the switch so provided has the capability of being manually actuated, children may open the closure and start the appliance with the closure still open, whereby they may be injured by the moving parts thereof. In order to overcome this problem, a wide variety of complex and highly intricate switch mechanisms and systems have been developed, a substantial number of which combine an electrical switch with the closure-hinge means whereby the switch and switch actuator are positioned out of the reach of an operator. However, such intricate switch mechanisms are usually expensive and are frequently so complicated as to be unreliable in operation.

It is therefore an object of the present invention to provide a new and improved, simple and inexpensive safety switch means adapted to terminate the operation of an appliance when the closure is moved from the closed position.

It is a further object of this invention to provide such a switch means as is not readily manually operable by an operator when the closure is in the open position.

It is still a further object to provide such an improved switch means having cabinet-carried and closure-carried components which are self-aligning thereby alleviating the need for close-tolerance-manufacturing alignment of such components.

SUMMARY OF THE INVENTION

Briefly stated, in accordance with one aspect of the present invention, there is provided in a domestic appliance including a cabinet having an opening therethrough to the interior of the appliance and having a closure member adapted to move between an open position and a closed position to control access through the opening to the interior of the cabinet, and wherein the closure member in its closed position serves to cover not only the opening but also a portion of the cabinet, the improvement of a safety-switch means adapted to terminate the operation of the appliance when the closure is moved from the closed position. The switch means comprises a relatively large aperture through the portion of the cabinet covered by the closure member when in the closed position, and an escutcheon member positioned within the opening and adapted for movement relative thereto a limited distance in all directions. The escutcheon is adapted to engage and cover the entire periphery of the opening at all times regardless of its position within the opening. The escutcheon additionally has a substantially centrally located aperture formed therethrough, the aperture being tapered to provide a relatively large outer diameter facing the closure member and a relatively small inner diameter adjacent the interior of the cabinet. An electrical switch is disposed within the cabinet and has an actuator of relatively large diameter positioned adjacent the inner diameter of the aperture so as to be aligned with the aperture regardless of the position of the escutcheon within the opening, whereby access to the switch actuator may be had only through the aperture. The inner diameter of the aperture is sufficiently small to prevent manual operation of the switch by an operator attempting to extend his finger through the aperture. An elongate projection of relatively small diameter and carried by the closure is adapted to engage the tapered aperture and to move the escutcheon so as to align the relatively

small inner diameter therewith when the closure is closed, thereby enabling the projection to extend through the aperture and contact the switch actuator to operate the switch.

BRIEF DESCRIPTION OF THE DRAWING

While the specification concludes with claims particularly pointing out and distinctly claiming the subject matter which is regarded as the invention, it is believed the invention will be better understood from the following description of the preferred embodiment taken in conjunction with the accompanying drawing, in which:

FIG. 1 is a partial perspective view of a fabric-washing machine which may include the safety switch means of the instant invention; and

FIG. 2 is a fragmentary view, partially in cross section, and taken along line 2-2 of FIG. 1 showing the closure member of the machine of FIG. 1 in a partially open position.

DESCRIPTION OF THE PREFERRED EMBODIMENT

Referring now to the drawing, and initially to FIG. 1 thereof, there is illustrated a typical domestic automatic fabric-washing machine 10 including a cabinet 11 which encloses a typical fabric-washing apparatus (not shown). As is well known in the art, the fabric-washing apparatus may include a container mounted within cabinet 11 for rotation therein, an agitator positioned within the container, and electrically operated drive means adapted to rotate the container and agitator for washing fabrics within the container and for centrifugally extracting liquid therefrom.

Extending upwardly from the rear portion of cabinet 11 is a typical control console 12 which may support and house a series of control means 13, 14, and 15. Such control means are included in the usual manner to provide effective operative control of the sequence of operations performed by the apparatus contained within the cabinet 11.

The top of cabinet 11 has an opening 16 formed therethrough to the interior of the machine. A closure member 17 is pivotally mounted so as to move between an open position and a closed position to control access through the opening 16 to the interior of the cabinet. The closure member 17 in its closed position serves to cover not only the opening 16 but also a portion 18 of the cabinet 11 adjacent the opening. As may be best seen in FIG. 2, portion 18 may comprise a recessed region which terminates in a downwardly flared substantially annular lip 19 defining opening 16. Closure 17 may comprise an inverted pan-shaped structure, and the pivotal connection between closure 17 and the cabinet 11 may be formed by a pair of brackets 20, the outer ends 21 of which rigidly connect to opposite sides of the closure 17 and the inner ends 22 of which pivotally connect with brackets 23 secured to cabinet 11. Intermediate ends 21 and 22, brackets 20 extend through openings 24 formed in portion 18 and through the apertures of flexible members 26 positioned in the slots 24.

As was previously pointed out, it is desirable in connection with such appliances as washing machine 10 to provide a closure-operated safety switch means which will terminate the operation of the appliance when the closure is moved from the closed position. In accordance with the present invention, such a safety switch means is provided which is simple and inexpensive in design and which is adapted to prevent manual restarting of the appliance by an operator when the closure is moved from the closed position. In particular, a safety switch means indicated generally by the numeral 27 may include a closure-carried elongate projection 28 adapted to extend through an opening 29 in portion 18 so as to engage a switch actuator 30 of switch 31 when the closure 17 is in the closed position. Switch 31 may be rigidly secured to an inwardly turned flange 32 of cabinet 11 and in a conventional way may be connected in electrical series with the drive means of the machine 10 so as to terminate the operation of the machine when the closure is moved from the closed position causing projection 28 to disengage switch actuator 30.

Opening 29 through portion 18 is relatively large in diameter to the diameter of elongate projection 28 which passes therethrough. In order to close the area of opening 29 not occupied by projection 28, and in order to prevent manual operation of switch 31 by an operator projecting his finger through opening 29 and into contact with switch actuator 30, a specially designed escutcheon member 33 is provided. Escutcheon member 33 is positioned within opening 29 and is adapted for movement relative thereto a limited distance in all directions, it being seen that a radially extending groove 34 adapted to receive such area of portion 18 as surrounds opening 29 extends inwardly to an inner diameter which is substantially less than that of opening 29. Moreover, the outer periphery of escutcheon 33 is seen to be of relatively large diameter such that the escutcheon is adapted to engage and cover the entire periphery of opening 29, regardless of the lateral position of the escutcheon 33 within opening 29. Escutcheon 33 additionally includes a centrally located aperture 35 formed therethrough, the aperture 35 being tapered to provide a relatively large outer diameter-facing closure member 17 and a relatively small inner diameter adjacent the interior of the cabinet.

Elongate projection 28 is carried by closure 17 by means of a bracket 36 rigidly secured thereto, and comprises a relatively long pan-shaped projection having a rounded, bluntly pointed, lower end adapted to engage tapered aperture 35 so as to move escutcheon 33 laterally relative to portion 18 so as to align escutcheon 33 with projection 28 thereby permitting projection 28 to extend through the relatively small inner diameter of aperture 35 and into contact with switch actuator 30 which is of relatively large diameter and is positioned adjacent the inner diameter of aperture 35 so as to be aligned with aperture 35 regardless of the position of escutcheon 33 within opening 29. By this arrangement, access to switch actuator 30 may be had only through aperture 35, and aperture 35 is seen to be self-aligning with projection 28 so as to facilitate the operation of switch 31 upon movement of closure 17.

The present invention thereby provides two significant advantages over most known safety switch means. Firstly, it will be seen that cabinet-carried escutcheon 33 is self-aligning with closure-carried projection 28 whereby close tolerance adjustment of the relative positions of these members is not critical and the members may thereby be manufactured and assembled with a minimum of expense. Secondly, as aperture 35 is tapered with the inner diameter thereof being of relatively small dimension, it will be seen that switch actuator 30 is not readily accessible to an operator who may desire to restart the appliance with closure 17 open by attempting to project his finger through aperture 35 and into engagement with switch actuator 30. Moreover, escutcheon member 33 may be constructed of a material which is sufficiently rigid to prevent manual operation of the switch by depression of the escutcheon through opening 29 and into engagement with switch actuator 30.

From the foregoing description, it should now be apparent that the present invention, by providing a safety-switch means having cabinet-carried and closure-carried components thereof which are self-aligning, and by providing limited access to the switch actuator by means of a specially designed escutcheon having a tapered opening, provides a safety switch means which is simple and inexpensive in design and which is highly reliable in operation.

As will be evident from the foregoing description, certain aspects of the invention are not limited to the particular details of construction of the example illustrated, and it is contemplated that various modifications or alternate applications will occur to those skilled in the art. It is therefore intended that the appended claims shall cover such modifications and applications as do not depart from the true spirit and scope of the invention.

What is claimed as new and desired to be secured by Letters Patent of the United States is:

1. In a domestic automatic appliance including a cabinet having an opening therethrough to the interior of the appliance and having a closure member adapted to move between an open position and a closed position to control access through the opening to the interior of the cabinet, the closure member in its closed position serving to cover not only the opening but also a portion of the cabinet, the improvement of a safety switch means adapted to terminate the operation of the appliance when the closure member is moved from the closed position, the switch means comprising:

a relatively large opening formed through the portion of the cabinet covered by the closure member when in the closed position;

an escutcheon member positioned within said opening and adapted for movement relative thereto a limited distance in all directions, said escutcheon member being adapted to engage and cover the entire periphery of said opening at all times regardless of its position within said opening; said escutcheon member additionally having a substantially centrally located aperture formed therethrough, said aperture being tapered to provide a relatively large outer diameter facing the closure member and a relatively small inner diameter adjacent the interior of the cabinet;

an electrical switch disposed within the cabinet and having an actuator of relatively large diameter positioned adjacent the inner diameter of said aperture so as to be aligned with said aperture regardless of the position of said escutcheon member within said opening, whereby access to said switch actuator may be had only through said aperture;

said inner diameter of said aperture being sufficiently small to prevent manual operation of said switch by an operator attempting to extend his finger through said aperture; and an elongate projection of relatively small diameter carried by the closure member and adapted to engage said tapered aperture and to move said escutcheon member so as to align said relatively small inner diameter therewith when the closure member is closed, thereby enabling said projection to extend through said aperture and contact said switch actuator to operate said switch.

2. The invention of claim 1 wherein said escutcheon member comprises a material which is sufficiently rigid to prevent manual operation of said switch by the depression of said escutcheon through said opening into engagement with said switch actuator.

3. In a centrifuging device including a cabinet having an opening therethrough to the interior of the device and having a closure member adapted to move between an open position and a closed position to control access through the opening to the interior of the cabinet, the closure member in its closed position serving to cover not only the opening but also a portion of the cabinet, a container mounted within the cabinet for rotation, and electrically operated drive means adapted to rotate the container, the improvement of a safety-switch means connected in electrical series with the drive means and adapted to terminate the operation of the device when the closure member is moved from the closed position, the switch means comprising:

a relatively large opening formed through the portion of the cabinet covered by the closure member when in the closed position;

an escutcheon member positioned within said opening and adapted for movement relative thereto a limited distance in all directions, said escutcheon member being adapted to engage and cover the entire periphery of said opening at all times regardless of its position within said opening; said escutcheon member additionally having a substantially centrally located aperture formed therethrough, said aperture being tapered to provide a relatively large outer diameter facing the closure member and a relatively small inner diameter adjacent the interior of the cabinet;

an electrical switch means disposed within the cabinet and having an actuator of relatively large diameter positioned

adjacent the inner diameter of said aperture so as to be aligned with said aperture regardless of the position of said escutcheon member within said opening, whereby access to said switch actuator may be had only through said aperture;

said inner diameter of said aperture being sufficiently small to prevent manual operation of said electrical switch means by an operator attempting to extend his finger through said aperture; and

an elongate projection of relatively small diameter carried by the closure member and adapted to engage said tapered aperture and to move said escutcheon member so as to align said relatively small inner diameter therewith when the closure is closed, thereby enabling said projection to extend through said aperture and contact said switch actuator to operate said electrical switch means.
